CLAIM

The ornamental design for a car cellphone bracket as shown and described.

DESCRIPTION

FIG. 1 is a top, front and right side perspective view of a car cellphone bracket showing our new design;

FIG. 2 is a bottom, rear and right side perspective view thereof;

FIG. 3 is a bottom, front and left side perspective view thereof;

FIG. 4 is a top, rear and left side perspective view thereof;

FIG. 5 is a front elevational view thereof;

FIG. 6 is a rear elevational view thereof;

FIG. 7 is a left side view thereof;

FIG. 8 is a right side view thereof;

FIG. 9 is a top plan view thereof;

FIG. 10 is a bottom plan view thereof;

FIG. 11 is a top, front and right side perspective view showing the car cellphone bracket in a position of use; and, FIG. 12 is an enlarged view of portion 12 in FIG. 1.

The broken lines in FIGS. 2 and 10 illustrate portions of the car cellphone bracket which form no part of the claimed design.

The broken lines in FIG. 11 depict environment and are for illustrative purposes only and form no part of the claimed design.

The dot-dashed lines illustrate the boundary of the enlarged detail views and form no part of the claimed design.
